Patented Dec. 13, 1955

176,333

UTILITY HEADBOARD

Ernest Herrmann, Hillsdale, N. J., assignor to Heywood-Wakefield Company, Gardner, Mass., a corporation of Massachusetts

Application March 14, 1955, Serial No. 35,036

Term of patent 7 years

(Cl. D5—4)

Fig. 1 is a perspective view of a utility headboard showing my new design, with a bed shown in phantom for illustrative purposes only.

Fig. 2 is a view in front elevation of my new design on a scale larger than that of Fig. 1.

Fig. 3 is a top plan view of my new design on the scale of Fig. 2.

Fig. 4 is a vertical sectional view on the line 4—4 of Fig. 2 and on the same scale, and

Fig. 5 is a perspective view of one of the knobs in my new design.

The stippling on the outer end portion of the knob is intended to illustrate a concave area having a dull white surface which contrasts with the side portion of the

knob, the shading of which is intended to illustrate a metal surface, such as bright brass.

I claim:

The ornamental design for a utility headboard substantially as shown and described.
